[57] CLAIM

The ornamental design for a support for flexible containers, substantially as shown.

DESCRIPTION

FIG. 1 is a perspective view of a support for flexible containers showing my new design, the broken lines representing a container are for illustrative purposes only and form no part of the design;

FIG. 2 is a top plan view thereof;

FIG. 3 is a side elevational view thereof, the opposite side being a mirror image of that shown;

FIG. 4 is a rear elevational view thereof; and

FIG. 5 is a bottom plan view thereof.
